DESIGN FOR A PIANO CASE

Peter Van Dommelen, Holland, Mich., assignor to Gulbransen Company, Chicago, Ill., a corporation of Illinois

Application August 28, 1936, Serial No. 64,612

Term of patent 3½ years

To all whom it may concern:

Be it known that I, Peter Van Dommelen, a citizen of the United States, residing at Holland, in the county of Ottawa and State of Michigan, have invented a new, original, and ornamental Design for a Piano Case, of which the following is a specification, reference being had to the accompanying drawing, forming a part thereof, and in which:

I claim:

The ornamental design for a piano case, as shown.

PETER VAN DOMMELLEN.
